ALFRED H. WILLETT, OF WEST ENGLEWOOD, NEW JERSEY, ASSIGNOR TO AMERICAN ARCH COMPANY, OF NEW YORK, N. Y., A CORPORATION OF DELAWARE

LOCOMOTIVE ARCH CONSTRUCTION

Application filed September 22, 1927. Serial No. 221,174.

This invention has reference to an improved locomotive arch construction and particularly to the formation of the refractory brick used in such locomotive arch whereby 5 to increase the adaptability of said brick to different tube spacings and also to avoid difficulties which have been encountered in the standard or commonly used form of brick due to alterations in the supporting surfaces 10 at the time of the formation or burning of the brick.

In the usual construction of middle brick for locomotive arches known in the trade as the "M" brick pattern, there is a curved socket- 15 et at one end which embraces or rests upon a supporting arch tube and an inclined or bevelled part at the other end resting upon the adjacent tube to give a certain degree of adjustability or adaptability to different tube 20 spacings as the inclined surface rides up or down on the tube upon which it rests.

It has been found in practice that the socket end of these "M" brick patterns or structures (which is designed for a substantially snug fit upon the supporting tube on which it rests) is not uniform, mainly because this portion is particularly subjected to distortion in the course of manufacture especially in the burning of the brick in the 25 kiln. Furthermore such socket ends when made to fit a tube of a certain diameter do not seat properly on tubes of other diameters. These difficulties have led to the suggestion in some instances, of the substitution of a bevelled end at both ends of the brick in place 30 of the bevelled end and socket, but this as heretofore proposed has been open to the difficulty of allowing the brick to become displaced and fall thru between the tubes, when 35 it bounces up and down in the service of the locomotive.

The primary object of my present invention is to secure the advantages of a brick having a bevelled supporting surface at one 45 or both ends, by providing in association therewith suitable means preferably in the shape of an upper and lower projection which will avoid displacement.

In order that my invention may be better 50 understood, I will now proceed to describe

the same in connection with the accompanying drawings, in which

Fig. 1 is a transverse sectional view thru the fire box of a locomotive showing four arch supporting tubes with a series of middle 55 brick and side brick carried thereby.

Fig. 2 is an enlarged view of one of the middle bricks resting upon two of the tubes, and

Fig. 3 is an inverted plan view of the brick 60 shown in Fig. 2, on a somewhat smaller scale.

Referring now more particularly to Fig. 1, it will be seen that I have therein indicated at 4 the side sheets of the locomotive 65 fire box against which, on either side, are rested in inclined position, the side brick 5, the inner ends of which are carried by arch supporting tubes 6, the spaces between which in the middle of the arch, are bridged across 70 or closed by means of the "M" or middle brick 7 of which there are a series of rows in the usual relation.

Referring to Fig. 2 it will be seen that on either end of the brick 7 I have provided a sloping or inclined supporting surface 8 adapted to rest against the curved outer surface of the tube 6, this supporting surface being of considerable length diagonally so that if the tubes are of different spacings, as indicated by the dotted line, the brick will still be properly held in position, there being, however, a limit to the movement and a protection for the placement of the brick involved in the provision of the projections 9 85 and 9a at the top and bottom which come into contact with the tubes at the extreme position of the brick. These projections will serve the purpose of arresting any sliding movement of the brick or any displacement 90

motion such as would perhaps occur from bouncing of the locomotive in service and will thus prevent the brick from falling out of place between the tubes. The projections 9a will resist any tendency of the brick to 95 bounce upwardly or laterally away from position while the projections 9 on the upper side of the brick will act similarly in a downward direction.

It will be seen that in Fig. 2 there is quite 100

a difference in the spacing of the tubes shown in full lines as compared with the tubes shown in dotted lines and in practice I have found it possible to get a very wide range 5 of variation with the use of the same brick which, of course, reduces the number of patterns which have to be carried in stock. In addition, the bricks here disclosed, either side or middle brick, will readily fit tubes of different diameters.

I claim:

1. A locomotive arch construction including spaced-apart arch tubes, and a refractory brick extending between tubes; each end of 15 said brick having a surface tangent to a tube and inclined between the vertical and horizontal for sliding adjustment between brick and tube, and, at each end of the brick, a pair of ribs projecting beyond the inclined 20 surface; one extending along the upper and one along the lower edge thereof, respectively, the distance between the ribs of a pair bearing such a relation to the tube diameter that at least one rib of the pair will be out 25 of contact with the tube in any normal position of the brick.
2. In combination with a pair of locomotive arch supporting members, a refractory brick having means of adjustable contact 30 with said supporting members at each end of the brick, said means on at least one end of the brick including an inclined surface in sliding contact with the respective member, and projections at said end at top and 35 bottom of said surface to prevent displacement of said brick from the supporting members.

In testimony whereof I have hereunto signed my name,

40 ALFRED H. WILLETT.
